COMPRESSOR DISCHARGE VALVE

John L. Klabon, Detroit, Mich., assignor to Norge Corporation, Detroit, Mich., a corporation of Michigan

Application November 26, 1930
Serial No. 498,219

3 Claims. (Cl. 230—149)

This invention relates to discharge valves for compressors and has special reference to improved quietness of operation when flapper valves are used in connection with rotary compressors.

The flapper valves heretofore in use have been found desirable for their efficiency in operation in connection with rotary compressors but undesirable from a noise standpoint when such compressors are used in domestic refrigeration apparatus. My invention, therefore, relates to an improved flapper valve arrangement which maintains or improves the efficiency of such valves while being much quieter in operation. It is, accordingly, an object of this invention to provide an improved form of flapper valve which is adapted to seat quietly while affording efficient discharge of the compressed fluid during the delivery period of the compressor.

It is another object of this invention to provide an improved form of discharge passage and valve for rotary compressors wherein clearance is provided for the escape of lubricant trapped between the rotor and the cylinder at the end of the compression period, thus preventing a sudden rise in pressure, with a consequent great improvement in the quietness of operation of the compressor.

It is a further object of this invention to provide an improved and simplified discharge valve arrangement for rotary compressors that will be economical to manufacture and assemble and that will not require excessively skilled servicing for maintenance.

Other and further important objects of this invention will be apparent from the disclosures in the specification and the accompanying drawings.

This invention (in a preferred form) is illustrated in the drawings and hereinafter more fully described.

On the drawings:

Fig. 1 is a central longitudinal section, partly in elevation, of a rotary compressor to which a discharge valve embodying one form of this invention has been applied.

Fig. 2 is an enlarged plan view of one face of the compressor cylinder proper, the oil reservoir housing having been removed.

Fig. 3 is an enlarged fragmentary section of the compressor on the line III—III of Fig. 1, to show the discharge passage leading to the valve.

Fig. 4 is an enlarged fragmentary section through the compressor end cover and valve housing, taken on the line IV—IV of Fig. 2.

Fig. 5 is an enlarged cross-section on the line V—V of Fig. 2.

Fig. 6 is a section on the line VI—VI of Fig. 4.

Fig. 7 is an enlarged fragmentary plane view of the compressor cylinder adjacent the blade, 60 with the cylinder cover in place but with the valve housing omitted.

As shown on the drawings:

The compressor chosen for illustrative purposes is of a rotary type and, in the form illustrated, is primarily intended to be belt driven as a part of domestic refrigeration apparatus wherein quietness and smoothness of operation is an essential quality. The exact type of compressor is immaterial to the present invention which relates to a discharge or check valve that operates with the minimum of noise compatible with the maximum efficiency in operation.

The illustrated compressor structure comprises a body 11 having a central cylindrical bore 12 with outstanding end flanges 13, the faces of which are finished parallel to each other and at right angles to the cylindrical bore, the perimeter of the flanges being finished concentric with the bore to provide locating shoulders for end closures 80 containing bearings for a compressor shaft 14. A back closure 15 is shown in elevation in Fig. 1, while a front closure 16 is formed as a lubricant reservoir or housing containing a stuffing box 17 and shaft seal 18 as well as a shaft bearing 85 19 concentric with the cylindrical bore. The shaft carries an eccentric 20 within the cylindrical bore, on which eccentric is mounted a rotor or sleeve 21 which is so proportioned as to just clear the cylinder wall at the position of maximum eccentricity of the eccentric. This sleeve floats on the eccentric and is, therefore, free to roll within the cylindrical bore as it is oscillated therein by the rotation of the shaft and eccentric. In practice it is approximately stationary relative to the part generating the greatest friction, which is usually the partition blade 22. This blade is slidably mounted in a slot 23 in the cylinder which slot terminates in a drilled hole 24 which admits lubricant back of 100 the blade. A spring 25 is so positioned in a boss 26 as to act against the blade to supplement the pressure of the lubricant thereon to cause the blade to maintain contact with the sleeve or rotor 21.

End seals or covers 27 are applied to each flange 13 of the body in the form of annular plates which make sealing contact with the rotor sleeve 21 while having ample clearance from the shaft itself. The end seal on the discharge 110

side is formed with a discharge port 28 over which a discharge valve housing 29 is applied, the housing having an apertured boss 30 into which a tube 31 is sealed which tube leads the discharge into the upper part of the reservoir 16 above the lubricant level therein. The port 28 is on the discharge side of the partition blade, while a suction passage 32 opens into the compression space on the opposite side of the blade. 10 The discharge port 28 in the end cover is offset to one side of the housing boss aperture 33, as best shown in Fig. 6, and is chamfered towards the aperture. A flapper valve 34 is positioned over the port in a shallow pocket 35 in the housing and is pinned at 34^a to the cover at one end, the valve being thus offset relative to the housing aperture 33. A relief slot 36 is cut in the housing along the edge of the valve which is located substantially centrally of the aperture 33 because of this offset. A light coil spring 37 is so positioned in a pocket 38 as to engage the edge of the valve on the side opposite the relief slot. This arrangement causes the valve to open sideways by a twisting movement since one edge is lightly held down by the spring 37, so that spring snap or pounding is prevented, a smoother and quieter valve action resulting.

Quietness of valve action is further assured by providing a semi-circular slot 39 in the cylinder body beneath the port 28 and alongside the partition blade—this slot connects with the compression space of the cylindrical bore through a slight clearance space 40 provided in the blade slot. The compressed gas thus passes through the clearance space 40 over the full width of the cylinder, into the slot 39 and thence to the port 28 rather than directly through the port 28 from the cylinder as heretofore. With this arrangement the clearance volume so provided serves to reduce wire drawing during the brief discharge interval wherein the compressor pressure exceeds the back pressure normally holding the discharge valve closed. The clearance space is also highly advantageous in case excess lubricant is present in the compressor cylinder as may be the case after a shut-down period. It has been found by experiment that the clearance space should be directly adjacent the cylinder proper rather than in enlarged passages in the end closure.

The operation of the compressor proper is well known and hardly needs description. The discharge valve of this invention serves to prevent back flow of compressed gases from the reservoir 16 and is normally seated by such back pressure except during short intervals when the compressor develops a pressure sufficient to unseat the valve. The valve then opens sideways due to the offset location and unbalanced condition introduced by the spring 37 so that the discharge from the port 28 passes under the edge of the valve into the relief slot 36 and thence into the aperture 33 and tube 31. The clearance space provided between the compressor cylinder proper and the port 28 is also an important factor in the quietness of operation of the valve as it reduces wire drawing of the compressed gases and the impact of entrained liquids on the valve.

This application differs from the copending

Buchanan et al. application Serial No. 509,612, entitled "Discharge valves", filed January 19, 1931, in that the valve opens by a torsionally twisting motion whereas in the copending application the valve opens by buckling up in the center.

It will thus be seen that I have invented an improved compressor discharge valve that represents a great improvement in quietness of operation.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A discharge valve of the elongated strip type pinned at one end and adapted to control a valve seat in the outlet passage of a pump having a compression space completely swept by fluid impelling means, including a fluid receiving space in immediate proximity to the compression space and extending across the width thereof, said fluid receiving space forming part of the outlet passage leading to the valve seat, said fluid receiving space being provided to cushion and reduce liquid hammer on both the pump and the discharge valve, and pressure means acting on one side of the elongated strip valve intermediate the length thereof and adjacent the discharge port whereby to cause said valve to open by a transverse twisting movement in the region of the valve port whereby to prevent valve slap.

2. A discharge valve of the straight strip type pinned at one end and adapted to control a valve seat in the outlet passage of a pump having a compression space completely swept by fluid impelling means, including a fluid receiving space in immediate proximity to the compression space, said fluid receiving space forming part of the outlet passage leading to the valve seat, said fluid receiving space being provided to cushion and reduce liquid hammer on both the pump and the discharge valve, and pressure means acting on one side of the straight strip valve intermediate the length thereof and adjacent the discharge port whereby to cause said valve to open by a transverse twisting movement in the region of the valve port whereby to prevent valve slap.

3. A discharge valve of the elongated strip type pinned at one end and adapted to control a valve seat formed as a plane surface about the outlet passage of a pump having a compression space completely swept by fluid impelling means, including a fluid receiving space in immediate proximity to the compression space, said fluid receiving space forming part of the outlet passage leading to the valve seat, said fluid receiving space being provided to cushion and reduce liquid hammer on both the pump and the discharge valve, and resilient loading means engaging one side of said valve intermediate the length thereof and adjacent the valve seat to cause a torsionally twisting opening movement of the valve in the region of the valve seat.

JOHN L. KLABON.
